(57) **CLAIM**

The ornamental design for an upper rear bumper cover, as shown and described.

DESCRIPTION

FIG. 1 is a front perspective view of an upper rear bumper cover showing our new design;

FIG. 2 is a side perspective view thereof;

FIG. 3 is a front elevational view thereof;

FIG. 4 is a side elevational view thereof;

FIG. 5 is an opposite side elevational view thereof;

FIG. 6 is top plan view thereof; and,

FIG. 7 is a bottom plan view thereof.

It will be understood that the broken lines shown in the drawings illustrate portions of an upper rear bumper cover that form no part of the claimed design.
